UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

SWINGING TRACK AND BOOM FOR LITTER-CARRIERS AND THE LIKE.

1,006,837.

Specification of Letters Patent. Patented Oct. 24, 1911.

Application filed May 20, 1911. Serial No. 628,401.

To all whom it may concern:

Be it known that I, HENRY L. FERRIS, a citizen of the United States, residing at Harvard, in the county of McHenry and State of Illinois, have invented a new and useful Improvement in Swinging Tracks and Booms for Litter-Carriers and the Like, of which the following is a specification.

My invention relates to certain new and useful improvements in a swinging track and boom for litter-carriers and the like, and is fully described and explained in the specification and shown in the accompanying drawings, in which:

15 Figure 1 is a side elevation of my improved device; Fig. 2 is a horizontal section on the line 2 of Fig. 1; Fig. 3 is a detailed side elevation of the parts adjacent to the boom pivots; Fig. 4 is a top plan of the 20 parts shown in Fig. 3; Fig. 5 is a vertical section on the line 5 of Fig. 4; Fig. 6 is a transverse section on the line 6 of Fig. 1; Fig. 7 is a top plan of the parts shown in Fig. 6; Fig. 8 is a vertical transverse section 25 on the line 8 of Fig. 7; Fig. 9 is a section on the line 9 of Fig. 3; Fig. 10 is a horizontal section on the line 10 of Fig. 1; Fig. 11 is a transverse vertical section on the line 11 of Fig. 10; Fig. 12 is a similar section 30 on the line 12 of Fig. 10; Fig. 13 is a side elevation of the guy-supporting device; Fig. 14 is a section on the line 14 of Fig. 13, and Fig. 15 is a transverse section corresponding to Fig. 9 through a modified 35 form of the boom.

Referring to the drawings, 16 is a barn-wall provided with a door-opening just above which is a stationary pivot-member 17 arched to embrace a barn-door hanger-rail in accordance with what is now approved practice.

18 and 19 are two swinging hinge-members provided with ears 20 engaged by a pivot-pin 21 whereby they receive pivotal support from the stationary hinge-member 17. The two members 18 and 19 are each, in the preferred form of construction, right-angled in cross-sections to embrace angle-irons which together form the boom. The 45 members 18 and 19 are provided with laterally-extending ears 22 and are held together by vertically-extending bolts 23.

The two angle-irons, of which the boom

proper is composed, are placed with their open sides together and their angles apart 55 with a slot between them vertically. The various devices which hold these two angle-irons in a solid and substantial construction, are formed so as to embrace their outsides, after the manner of the members 18 60 and 19 of the swinging hinge-members, and these various devices are held together by bolts passed between the angle-irons and clamping the various embracing devices onto the separated edges thereof, with the 65 result that the angle-irons are pressed together and thus squeeze against the various bolts so that the strongest possible construction is obtained.

The devices which hold the angle-irons 70 together are all, or practically all, so arranged as to serve other purposes as well. Thus the track is supported by brackets 24, each in the form of a bolt having a shoulder 24^a below the angle-irons of the boom and 75 having its upper end passed therebetween. This bracket construction is fully illustrated in Figs. 3 and 9, where it will be seen that above the shoulder 24^a of each bracket is a boom-clamping member 25 embracing the 80 outsides of the angle-irons thereof, along the separated edges, and that above the boom is a similar boom-clamping member 26 held down by a nut 27. These various brackets are spaced at convenient intervals and support the track 28, in the manner 85 illustrated. The track is preferably of the slotted form of a now approved type for feed and litter-carrier use, and it is manifest that by the use of this boom and track 90 in combination, the brackets may be adjusted longitudinally as desired. In addition to the brackets and other attaching means there are provided guy-fastenings, at intervals in accordance with the length of the 95 boom. These consist of lower members 29 and upper members 30, the lower members 29 being like the boom-clamping members which secure the brackets in position, and the upper members being similar thereto but 100 provided with eyes. The two parts of the guy-fastenings are held together by bolts and contribute to the rigidity and strength of the boom. There are also provided truss-members, each of which has at its center 105 boom-engaging members 31 formed to em-

•

18 and 19 are two swinging hinge-members provided with ears 20 engaged by a pivot-pin 21 whereby they receive pivotal support from the stationary hinge-member 17. The two members 18 and 19 are each, in the preferred form of construction, right-angled in cross-sections to embrace angle-irons which together form the boom. The 45 members 18 and 19 are provided with laterally-extending ears 22 and are held together by vertically-extending bolts 23.

The two angle-irons, of which the boom

brace the boom and to be held together by bolts, as already set forth. Each of the members 31 is provided with a laterally-extending flange in which is a semi-cylindrical groove, the grooves of each two opposing flanges receiving laterally-extending tubes or pipes 32. Each pipe 32 has at its end a vertically-extending cross-bar 33 around which is passed a loop 34 threaded 10 at its two ends. A truss-clamp 35 is passed over the two ends of the loop 34 and held in position by nuts on the thread ends of said loop, so as to clamp between itself and the ends of the tubes or pipes 32, a truss-rope or wire 36, the inner end of which is secured by a turn-buckle 37 to the ears 22 of the swinging-hinge members of the boom and the outer end of which is secured to bolts 38 at the outer end of the boom. The 15 manner in which these bolts 38 are supported is illustrated in Figs. 10 and 11, where it will be seen that the extreme end bracket has its boom-clamping members 39 and 40 extended outward to form lateral ears between 20 which the bolts 38 are passed, spreaders being provided around the bolts so as to receive the ends of the truss over the wires.

By the foregoing construction a simple and efficient device is provided. The boom 30 is exceedingly strong inherently and it is trussed and guyed so as to eliminate any danger of buckling. The track within the barn is connected to the track outside the barn, as illustrated, in accordance with common practice of the present day.

In order to permit the swinging of the boom to occur without unnecessary wear of the guy-ropes, these ropes are secured to a pivoted loop 41 which receives its support 40 from a bracket 42 fast on the barn-wall. As the boom is swung the guys on the loop 41 turn therewith so that the guy-ropes do not swing upon any stationary pivot, as has been the case heretofore.

I am aware that considerable variation is possible in the present construction which I have described in detail as the preferred embodiment of my invention. By such detailed description, however, I do not intend 50 to limit myself to the specific form indicated, my intention being on the contrary to claim all the novelty inherent in the construction as broadly as the state of the art will permit.

As one example of the variations in construction which are possible, I have shown in Fig. 15 a modified form of boom which is made of two T-beams, the heads of the T's being placed vertical and adjacent to each 60 other, and the remaining flanges turned outward. This affords a simple construction to which the various mechanisms herein described can readily be applied by modifying the boom-engaging parts after the manner 65 in which the corresponding parts are shown

in Fig. 15. Other variations will readily occur to mechanics skilled in the art.

What I claim as new and desire to secure by Letters Patent, is—

1. In combination a track, suspending 70 means therefor, a pivoted boom supporting the track-supporting means and consisting of two beams spaced apart horizontally and clamping means to hold said beams in fixed relation.

2. In combination a track, suspending means therefor, a pivoted boom consisting of two beams spaced apart horizontally and clamping means to hold the same in fixed relation, the suspending means for the track 80 passing between the two beams and forming part of the clamping means.

3. In combination two beams spaced apart horizontally, bolts extending vertically between the same, clamping devices held by 85 the bolts in engagement with the beams, and means to pivotally support the boom thus formed.

4. In combination two beams spaced apart horizontally, bolts extending vertically between the same, clamping devices held by 90 the bolts in engagement with the beams, means to pivotally support the boom thus formed, and a track below the boom, certain of the bolts aforesaid extending downward 95 to support the same.

5. In combination two angle-iron beams with their open faces opposed and spaced horizontally apart, clamping devices fitted to the edges of the angle-iron beams, bolts extending vertically between the same and lying between the beams to act as spreaders, and means for pivotally supporting the boom thus formed.

6. In combination two parallel rails spaced 105 apart horizontally, two hinge-members fitted thereto, a bolt passing vertically through the hinge-members and between the rails to clamp the members and to act as a rail spreader.

7. In combination two parallel rails spaced apart horizontally, two hinge-members fitted thereto, a bolt passing vertically through the hinge-members and between the rails to clamp the members and to act as a rail 115 spreader and eyes on the hinge-members to receive truss-wires.

8. In combination two parallel angle-iron rails spaced apart horizontally with their open sides opposing each other, two hinge-members fitted to the edges of the beams, a bolt passing between the hinge-members vertically and between the rails to clamp the hinge-members and act as a rail spreader.

9. In combination two rails spaced apart 125 horizontally and secured together to form a boom, and guy-fastenings, each consisting of two parts, one having an eye, and a bolt extending through the parts of the guy-fastenings between the rails to clamp the parts of 130

- the guy-fastenings together and to act as a rail spreader.
10. In combination two rails spaced apart, clamping means on opposite sides thereof, a bolt connecting the clamping means and acting as a rail spreader, tubes between the clamping means and extending laterally therefrom and truss-wire clamps located at the ends of the tubes.
11. In combination two rails spaced apart, clamping means on opposite sides thereof, a bolt connecting the clamping means and acting as a rail spreader, tubes between the clamping means and extending laterally therefrom, cross-bars in the tubes, U-shaped loops hooked over the cross-bars, and truss-wire clamps passed over the protruding ends of the U-shaped loops and adapted to engage truss-wires.
12. In combination a boom, tubes extending laterally therefrom and secured thereto, cross-bars in the tubes, U-shaped loops passed over the cross-bars and having their ends protruding from the ends of the tubes, truss-wire clamping means passed over the protruding ends of the U-shaped loops and adapted to engage truss-wires.
13. In combination a boom and a track, both consisting of parallel rails separated horizontally, clamping means engaging the boom-rails, bolts securing the said clamping
- means together and supports on the bolts for the track-rails.
14. In combination a pivoted boom, a track carried thereby, a rigid track, a connection between the rigid track and that carried by the boom, guy means from the boom to a point approximately above the boom pivot and a pivoted member to which the upper ends of the guys are attached.
15. In combination two angle-iron beams with their open faces opposed and spaced apart, clamping devices fitted to the edges of the angle-iron beams, bolts extending vertically between the same and lying between the beams to act as spreaders, and means for pivotally supporting the boom thus formed.
16. In combination two rails spaced apart, clamping means on opposite sides thereof, a bolt connecting the clamping means and acting as a rail spreader, and truss-spreading parts between the clamping means and extending laterally therefrom.

In testimony whereof I have hereunto set my hand this 1st day of May, 1911.

HENRY L. FERRIS.
